SEMAUTOMATIC STARTING CONTROL

Maurice P. Whitney, Elmira, N. Y., assignor to
Eclipse Machine Company, Elmira Heights,
N. Y., a corporation of New York

Application April 29, 1933, Serial No. 668,584

7 Claims. (Cl. 290—38)

The present invention relates to a semi-automatic starting control for internal combustion engines and more particularly to a protective device for a starter control to prevent undesired actuation of the starting mechanism.

In semi-automatic starter controls of the type in which the manual operation of an engine controlling element serves to start the engine in case of stall, it is desirable to incorporate protective features for preventing such operation of the starting mechanism at improper times such as when the engine is rotating backward. It is an object of the present invention to provide such a protective device which is efficient and reliable 10 while being simple in construction and readily applied to commercial forms of starter controls.

It is another object to provide such a device which automatically renders the starter control inoperative in response to a backfire or backward rotation of the engine.

It is a further object to provide such a device which restores the starter control to operative condition when the backfire or backward rotation of the engine has ceased.

25 It is another object to provide such a device which delays such restoration to operative condition for a predetermined time.

Further objects and advantages will be apparent to those skilled in this art from the following description taken in connection with the accompanying drawing in which:

Fig. 1 is a perspective view, partly diagrammatic, of a semi-automatic starter control embodying a preferred form of the present invention; and

Fig. 2 is a semi-diagrammatic illustration of a second embodiment of the invention, the backfire controlling element thereof being shown in enlarged section.

40 Referring first to Fig. 1 of the drawing, there is illustrated an internal combustion engine 1, of commercial form having a fuel intake system including an intake manifold 2. A manually operable member in the form of an accelerator pedal 4 is hinged at 5 to a floor board 6 and arranged to suitably engage a transmission element in the form of a plunger 7 slidably mounted in the floor board 6 and pivoted to a hinged supporting member 18 as indicated at 8. A throttle link 3 is pivoted to the plunger 7 as indicated at 9 and is arranged to operate the throttle of a carburetor, not illustrated, whereby depression of the accelerator pedal 4 causes admission of 50 fuel to the engine in the usual manner.

A starting system for the engine 1 is illustrated comprising a battery 11, grounded at 12 and connected by a lead 13 to a starting switch 14 mounted on a starting motor 15, which starting motor is provided with the usual gearing not 5 illustrated for engaging and cranking a member of the engine.

Semi-automatic means for closing the starting switch 14 by the operation of the manual control member 4 is provided in the form of connections which are normally in operative condition but which are disabled responsive to the self-operation of the engine. As here illustrated, these connections comprise a movable connecting element in the form of a lever 16 arranged normally in the path of an abutment 17 on the plunger 7 and hinged at 18 to a cross shaft 19 which is suitably journaled to the engine frame as indicated at 21 and 22. An operating lever 23 is suitably fixed to the end of shaft 19 as indicated 20 at 24 and has pivoted thereto at one end as indicated at 25 a link 26 arranged to engage the plunger 27 of the starting switch 14. The opposite end of lever 23 is preferably provided with suitable adjusting means 28 adapted to engage 25 a fixed stop member 29 in order to define the idle position of the lever.

Means are provided for disabling the connections responsive to intake vacuum of the engine by swinging the lever 16 out of the path of 30 abutment 17. As here shown this means comprises a link 31 suitably attached to the lever 16 as indicated at 32 and connected at its opposite end as indicated at 33 to a plunger 34 arranged to be retracted by a flexible diaphragm 35 forming one wall of a closed chamber 30 of a vacuum controlled device 36. Chamber 30 is connected by means of suitable tubing 37 and 38 to the intake manifold 2 of the engine whereby vacuum in said intake manifold causes the diaphragm 35 35 to be deflected in a direction to withdraw the lever 16 from its operative position.

According to the present invention, means are provided for disabling the connections from the accelerator pedal 4 to the starting switch 14 responsive to backfire or backward rotation of the engine by withdrawing the lever 16 from the path of movement of plunger 7, and preventing the return of said lever for a predetermined time. As here illustrated this is accomplished by providing independent electromagnetic means for withdrawing the lever 16 from operative position, responsive to pressure in the intake manifold of the engine caused by backfire or backward rotation thereof. This is accomplished as 55

shown in Fig. 1 by providing a solenoid 39 connected rigidly to the shaft 19, and by mounting a plunger 41 on the link 31 in position to be actuated by said solenoid to swing the lever 16 to anoperative position. A control circuit for the solenoid 39 is provided comprising battery 11, lead 42, manual switch 43 which is preferably the ignition switch of the engine, leads 44 and 45, contacts 46 and 47, lead 48 and ground connection 49. Contact 46 is mounted on a hinged armature 51 which is normally maintained in position to close contacts 46, 47 by suitable means such as a spring 52, but which is arranged to be opened by means of an electromagnet 53.

15 The electromagnet 53 normally energized when the ignition switch 43 is closed by means of a second control circuit including battery 1, ignition switch 43, lead 54, a circuit controlling device 55, lead 56 and ground connection 57 whereby contacts 46, 47 are normally held open while the engine ignition is on and the solenoid 39 thereby maintained deenergized.

20 The automatic circuit controlling device 55 constitutes switch means for breaking the control circuit of the solenoid 39 in response to pressure in the intake manifold. This device as best shown in Fig. 2, comprises a cylinder 58 having a piston 59 slidably mounted therein, said piston being provided with an upwardly projecting rod 61. A casing member 60 fixed to cylinder 58 carries two insulated binding posts 62 and 65. Binding post 62 carries a resilient strip of bimetal 63 on the free end of which is mounted a contact 64. The second binding post 65 carries 25 a fixed contact 66 with which contact 64 is normally in engagement whereby the control circuit for electromagnet 53 is normally closed.

30 Bimetal strip 63 carries near its free end a contact 67, and a contact 68 is mounted adjacent thereto on a spring strip 69 which is grounded to the casing 60 of the circuit controlling device. Spring strip 69 normally maintains contact 68 out of engagement with contact 67 but is arranged to be engaged by the upper end of piston rod 61 when the piston 59 is moved upwardly whereby contact 68 is caused to engage contact 67 pushing up the bimetal strip 63 and at the same time grounding the control circuit therethrough. The heavy current through the 35 bimetal strip 63 caused by such grounding of the circuit heats the bimetal causing it to bend away from contact 66 and the control circuit is opened at contacts 64, 66, both by the pushing up and the bending of bimetal strip 63, said circuit remaining open until the contact 68 has returned to its normal position and the bimetal has been permitted to cool off.

40 The controlling device 55 is connected to the intake manifold as illustrated in Fig. 1 preferably by means of a tube 72 whereby pressure in the intake manifold caused by backfire or backward rotation of the engine is transmitted to cylinder 58 to move piston 59 in a direction to close contacts 67, 68.

45 In the operation of the embodiment illustrated in Fig. 1, starting with the parts in the positions there shown, closure of ignition switch 43 completes the second control circuit through the circuit controlling device 55 thereby energizing electromagnet 53 to open contacts 46, 47. Solenoid 39 is thereby maintained deenergized and the lever 16 remains in operative position. Pressure by the operator on the accelerator pedal 4 therefor causes rotation of the shaft 19 which is 50 transmitted by lever 23 and link 26 to close the

starting switch 14 and cause the engine to be cranked in the usual manner. When the engine starts, the vacuum in the intake manifold 2 operates the vacuum controlled device 36 to withdraw the lever 16 whereupon the engine may 55 be controlled by the accelerator pedal in the usual manner.

Should the engine backfire or rotate backward the pressure generated thereby in the intake manifold causes the piston 59 of the circuit controlling device 55 to operate the rod 61 to move contact 68 into engagement with contact 67 thus pushing up and grounding the bimetal strip 63. Contacts 64, 66 are thus opened by the combined mechanical and heating effect of the engagement of contact 68 with contact 67. Electromagnet 53 is thereby deenergized causing contacts 46, 47 to close, thus completing the first control circuit through the solenoid 39. Energization of solenoid 39 causes the plunger 41 to move the link 31 in a direction to swing the lever 16 into inoperative position. Undesired operation of the starting mechanism is thus prevented during the continuation of the backward rotation of the engine and thereafter until the bimetal strip 63 has cooled off and permitted contacts 64 and 66 to reclose.

55 In Fig. 2 there is illustrated a second embodiment of the invention designed to eliminate the necessity for the relay contacts 46, 47. As herein illustrated the elements of the starter control and the means for disconnecting the same responsive to self-operation of the engine are the same as in Fig. 1 and are similarly numbered. The means for disabling the connection in case 60 of backfire, however, comprises in this case a solenoid 73 adapted to operate a plunger 74 which is loosely mounted on the link 31. An abutment 75 is provided on the link 31 for limiting movement of the plunger 74 in the releasing 65 direction, and a spring 76 bearing against the plunger and against a bracket 77 for solenoid 73 normally holds the plunger 74 against the stop 75, thus biasing the link 31 toward idle position as illustrated. Energization of the solenoid 73, 70 however, moves the plunger 74 away from the stop 75 thus permitting the lever 16 to be moved into its operative position by the resiliency of the diaphragm 35 or by any other suitable means.

A control circuit for solenoid 73 is provided 75 comprising the battery 11, lead 42, ignition switch 43, lead 78, circuit controlling device 55, lead 79 and ground connection 81. It will thus be seen that when the ignition switch 43 is closed, the solenoid 73 will be energized to withdraw the 80 plunger 74. However, when the circuit controlling device 55 opens contacts 64, 66, the solenoid 73 is deenergized and the spring 76 causes plunger 74 to move the link 31 to swing the lever 16 into inoperative position.

85 In the operation of this embodiment of the invention, closure of the ignition switch 43 places the starter control in operative condition by energization of solenoid 73. Operation of the accelerator pedal 4 thereupon causes starting of the engine in the usual manner. As soon as the engine becomes self-operative the vacuum device 36 withdraws the lever 16 to inoperative position whereupon the accelerator pedal is disconnected from the starting mechanism and is operated to 90 control the engine in the usual manner.

Should the engine backfire or rotate backward, the pressure generated thereby in the intake manifold 2 causes operation of the piston 59 of the circuit controlling device 55 to close contacts 75

67, 68, thereby opening contacts 64, 66, breaking the control circuit at that point. The consequent deenergization of solenoid 73 permits the spring 76 to move the plunger 74 and thereby cause the link 31 to withdraw the lever 16 to inoperative position. This inoperative condition is maintained until the pressure in the intake manifold 2 is dissipated and the bimetal strip cools off and allows contacts 64, 66 to reclose.

10 Although certain embodiments of the invention have been shown and described in detail, it will be understood that other embodiments are possible and changes may be made in the dimensions and arrangements of the parts without departing from the spirit of the invention as defined in the claims appended hereto.

What is claimed is:

1. In combination with an internal combustion engine, a manual control member therefor, a starting motor for said engine, connections whereby operation of the engine control member causes energization of the starting motor, means responsive to self-operation of the engine for disabling said connections, and independently operable means responsive to backward rotation of the engine for disabling said connection.

2. In combination with an internal combustion engine having a fuel intake system and an engine control member, starting mechanism for said engine, connections whereby operation of the engine control member causes actuation of the starting mechanism, means responsive to intake vacuum of the engine for disabling said connections and independent means responsive to positive pressure greater than atmospheric pressure in the intake of said engine to disable said connections.

3. In combination with an internal combustion engine having a fuel intake system and an engine control member, starting mechanism for said engine including a starting switch, connections whereby operation of the engine control member causes closure of the starting switch, including a transmission device movable by the engine control member and a movable connecting element normally in the path of movement of said transmission device, means responsive to forward rotation of the engine for withdrawing the connecting element from the path of the transmission device, and independent means responsive to reverse rotation of the engine for withdrawing the connecting element from the path of the transmission device.

4. In combination with an internal combustion engine having a fuel intake system and a control member therefor, starting mechanism for said engine including a starting switch, means for

closing said starting switch by operation of the engine control member, electromagnetic means for controlling said closing means, a control circuit for said electromagnetic means including switch means, and means responsive to positive pressure above atmospheric in the intake system of the engine for operating said switch means to cause said closing means to be disabled, and means responsive to vacuum in the intake system for disabling said closing means.

5. In combination with an internal combustion engine having a fuel intake system and an engine control member, starting mechanism therefor including a starting switch, connecting means for closing said starting switch by operation of the engine control member, means including an element movable in response to vacuum in the fuel intake system for disabling said connecting means, electromagnetic means for controlling the movement of said element, and a control circuit for said electromagnetic means including a manual switch means, switch means in series therewith, and means responsive to pressure in the intake system of the engine for operating said latter switch means.

6. In a semi-automatic starter control for internal combustion engines, an engine control member, a starter switch, connecting means including a movable lever member for closing the starting switch by operation of the control member, means for biasing said lever toward inoperative position, electromagnetic means for overcoming said biasing means, and a control circuit for said electromagnetic means including a manual switch, switch means responsive to backward rotation of the engine for opening said control circuit, and means responsive to forward rotation of the engine for moving said lever into inoperative position.

7. In combination with an internal combustion engine having a fuel intake system and an engine control member, starting mechanism for said engine including a starting switch, connections whereby operation of the engine control member causes closure of the starting switch including a transmission element movable by the engine control member, a movable connecting element and means for moving the connecting element into the path of movement of said transmission element, means responsive to reverse rotation of the engine for withdrawing the connecting element from the path of the transmission device and means for preventing return movement of the connection element for a predetermined time after such reverse rotation stops.

MAURICE P. WHITNEY.
